UNITED STATES PATENT OFFICE.

THEODORE C. ESENBERG, OF KANSAS CITY, MISSOURI.

DESIGN FOR A SIGNAL-LAMP FOR VEHICLES.

49,299.

Specification for Design.

Patented July 4, 1916.

Application filed March 20, 1916. Serial No. 85,525. Term of patent 3½ years.

To all whom it may concern:

Be it known that I, THEODORE C. ESENBERG, a citizen of the United States, residing at Kansas City, in the county of Jackson and State of Missouri, have invented a new, original, and ornamental Design for Signal-Lamps for Vehicles, of which the following is a specification, reference being had to the accompanying drawing, in which

the figure is a perspective view of a lamp showing my new design.

I claim:

The ornamental design for a signal lamp for vehicles, as shown.

THEODORE C. ESENBERG.

Witnesses:

FRED C. FISCHER,
L. J. FISCHER.
